(57) **CLAIM**

The ornamental design for a mobile phone case, as shown and described.

DESCRIPTIONFIG. 1 is a front, left-side, and bottom perspective view of a mobile phone case showing my new design;
FIG. 2 is a back, right-side, and top perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a back, right-side, and top perspective view thereof showing the back compartment in an open state; and,
FIG. 10 is an enlarged view of the selected portion in FIG. 1.

The broken lines shown in the drawings depict portions of the mobile phone case in which the design is embodied that form no part of the claimed design.
